UNITED STATES PATENT OFFICE.

CHARLES A. DORAN, OF CHICAGO, ILLINOIS, ASSIGNOR TO BAUER & BLACK, OF CHICAGO, ILLINOIS, A CORPORATION OF ILLINOIS.

WEFT-Straightening APPARATUS.

1,272,924.

Specification of Letters Patent. Patented July 16, 1918.

Application filed January 4, 1918. Serial No. 210,348.

To all whom it may concern:

Be it known that I, CHARLES A. DORAN, a citizen of the United States, residing at Chicago, in the county of Cook and State of Illinois, have invented certain new and useful Improvements in Weft-Straightening Apparatus, of which the following is a specification.

This invention relates to apparatus for straightening the weft of textile fabric after the bleaching operation, and is particularly adapted for use in connection with fabric such as surgical gauze.

Following the bleaching operation textile fabrics are washed, dried and wound on rolls. In winding, parts of the fabric tend to lag so that the weft threads are not straight as is desirable. To overcome this tendency it is customary to employ an operative for each web whose sole duty is to manually straighten the weft threads from time to time as may be necessary.

The object of my invention is to provide an apparatus which automatically straightens the weft threads when thrown into operation, thus permitting a single operative to control the winding of a plurality of webs.

A further object of my invention is the provision of a plurality of driving rolls adapted to be selectively moved by the operative into engagement with portions of the web to tension the respective portions and straighten the weft threads.

Further objects and advantages of my invention reside in the combinations hereinafter described as will be better understood by reference to the following specification, when read in connection with the accompanying drawing, illustrating the preferred embodiment thereof, in which—

Figure 1 is a plan view of the invention;

Fig. 2 is a section on the line 2—2 of Fig. 1;

Fig. 3 is an enlarged section through one of the web supporting rolls, and

Fig. 4 is a section on the line 4—4 of Fig. 3.

Referring to the drawing 5 indicates a suitable frame to support the various parts of the apparatus. A shaft 6 is journaled in the frame and is provided with a pulley 7 or other suitable means through which the shaft may be driven from a source of power,

Loosely mounted on the shaft 6 are a plurality of web supporting rolls 8 each provided with a facing 9 preferably of rubber. Adjacent each of the rolls 8 a ratchet 10 is secured to the shaft 6 in any suitable manner as for example by screws 11. The ratchets 10 are therefore driven with the shaft. Each of the web supporting rolls 8 is provided with a plurality of pawls 12 pivoted at 13 thereon and each having an arm 14 supporting a spring 15. The springs 15 are disposed between the pawls 12 and the peripheries of the web supporting rolls 8, and hold the pawls in engagement with the ratchets 10. Thus when the shaft 6 and ratchets 10 are driven in the direction indicated by the arrow in Fig. 4 the web supporting rolls 8 are driven in the same direction. The web supporting rolls are however, permitted to advance in the same direction independently of and at an angular speed greater than the angular speed of the shaft 6.

A shaft 16 is journaled in suitable bearings in brackets 17 secured to the frame 5. A pulley 17 is secured to the shaft 6 and is connected to a pulley 18 on the shaft 16 by a cross belt 19. Other suitable driving means may of course be substituted for the belt to drive the shaft 16 in the opposite direction to the direction of rotation of the shaft 6 and at a higher angular speed. A plurality of bifurcated arms 20 are loosely mounted on the shaft 16. Each arm 20 is provided with a weft straightening roller 21 having trunnions 22 journaled in the ends 90 of the arm 20. Sprockets 23 secured to each of the weft straightening rolls 21 are connected by chains 24 to sprockets 25 secured to the shaft 16. Thus the weft straightening rollers 21 are driven at the angular speed of the shaft 16 and are rotated in a direction opposite to the direction of rotation of the supporting rolls 8. The web supporting rolls 8 and weft straightening rollers 21 engage opposite sides of the web 26 and draw the web in the same direction as indicated by the arrow in Fig. 2.

Each of the arms 20 is provided with a tail 27 on which a counter weight 28 is supported and held by a set screw 29 so that the counter weights may be adjusted to exactly balance the weight of the arms 20 and weft straightening rollers 21. A rod 29 se-

cured in the bracket 17 carries a plurality of springs 20 which resiliently limit movement of the arms 20 in one direction by engagement of the tails 27 therewith.

5 The mode of operation of my invention will be readily understood from the following brief description thereof. The web 26 passes over the web supporting rolls 8 as indicated in Fig. 2. The operative examines 10 the web from time to time and upon finding that a portion of the web is lagging so that the weft threads are not straight swings the corresponding arm or arms 20 to carry the weft straightening roller or rollers 21 into 15 engagement with the web. Inasmuch as the peripheral speed of the weft straightening rollers 21 is considerably higher than the normal speed of the web 26 as it passes over the web supporting rolls 8 that portion of 20 the web with which the weft straightening roller or rollers 21 engages is tensioned and drawn forwardly at a higher rate of speed until the weft is again straight. The operative then swings the arm or arms 20 to disengage 25 the weft straightening roller or rollers 21 from the web. While a weft straightening roller 21 is in engagement with the web, the coöperating web supporting roll 8 is rotated at substantially the peripheral speed 30 of the weft straightening roller, the pawls 12 riding over the teeth of the ratchet 10.

From the foregoing description it will be readily understood that I have perfected a simple and effective means for straightening 35 the weft threads of textile fabrics. The apparatus may be rapidly thrown into and out of operation at the will of the operative and consequently a single operative may control the winding of a plurality of webs. Thus a 40 considerable economy is effected, and the winding is made more uniform than has been possible by following the practice of the prior art.

Various changes may be made in the form, 45 arrangement and construction of the parts without departing from the spirit or scope of the invention or sacrificing any of its material advantages, the form hereinbefore described being merely the preferred embodiment thereof.

I claim:

1. In a weft straightening apparatus for textile fabrics, the combination of a web support and means actuated independently 55 of the web and adjustable to engagement with the web at selected positions transversely thereof, and adapted to tension the portion of the web engaged, thereby straightening the weft threads.

60 2. In a weft straightening apparatus for textile fabrics, the combination of a web support and individually adjustable means actuated independently of the web and adapted to engage with the web at selected positions transversely thereof, and

adapted to tension the portion of the web engaged, thereby straightening the weft threads.

3. In a weft straightening apparatus for textile fabrics, the combination of a web support 70 and a plurality of driven rollers actuated independently of the webs and individually adjustable to engage the web at selected positions transversely thereof, and adapted to tension the portion of the web 75 engaged, thereby straightening the weft threads.

4. In a weft straightening apparatus, the combination of a web support comprising a plurality of driven rolls, and rotatable means 80 operating at a higher peripheral speed than said rolls, said means being adjustable to engage the web at selected positions transversely thereof, and adapted to tension the portion of the web engaged, thereby straightening the weft threads. 85

5. In a weft straightening apparatus, the combination of a web support comprising a plurality of driven rolls, a plurality of pivoted arms, weft straightening rollers supported by said arms, and means for driving 90 said weft straightening rollers at a peripheral speed higher than that of said driven rolls.

6. In a weft straightening apparatus, the combination of a web support comprising a shaft, a plurality of web supporting rolls loosely mounted on said shaft, one way driving connections between said shaft and rolls, and means coöperating with said rolls to 100 accelerate portions of the web as it passes said rolls, thereby straightening the weft threads.

7. In a weft straightening apparatus, the combination of a web support comprising a 105 plurality of web supporting rolls, driving means actuated independently thereof and therefor and means coöperating therewith to accelerate portions of the web as it passes said rolls, thereby straightening the weft 110 threads.

8. In a weft straightening apparatus, the combination of a web support comprising a shaft, a plurality of web supporting rolls loosely supported on said shaft, ratchets secured to said shaft, pawls on said rolls engaging said ratchets, and means coöperating with said rolls to accelerate portions of the web as it passes said rolls thereby straightening the weft threads. 115

9. In a weft straightening apparatus, the combination of a web support comprising a driven shaft, a plurality of web supporting rolls loosely supported on said shaft, pawl and ratchet mechanism providing a one way 125 driving connection between said shaft and web supporting rolls, a plurality of pivoted arms, and means carried thereby for engagement with the web and adapted to accelerate portions of the web as it passes said web 130

supporting rolls, thereby straightening the weft threads.

10. In a weft straightening apparatus, the combination of a web support comprising a driven shaft, a plurality of web supporting rolls loosely supported on said shaft, a one way driving connection between said shaft and web supporting rolls, a plurality of pivoted arms, a weft straightening roller carried by each of said arms, and means for driving said weft straightening rollers at a peripheral speed higher than that of said web supporting rolls, whereby portions of the web engaged by said weft straightening rollers are accelerated and the weft threads 15 are straightened.

CHARLES A. DORAN.
